CLAIM

The ornamental design for a skateboard, as shown and described.

DESCRIPTION

FIG. 1 is a front perspective view of a skateboard, which embodies my design.

FIG. 2 is a front view of the skateboard of FIG. 1.

FIG. 3 is a rear view of the skateboard of FIG. 1.

FIG. 4 is a right side view of the skateboard of FIG. 1. The left side view is a mirror image of the right side view.

FIG. 5 is a top view of the skateboard of FIG. 1; and,

FIG. 6 is a bottom view of the skateboard of FIG. 1.

Broken lines are used to illustrate portions of the skateboard which form no part of the claimed design.

1 Claim, 5 Drawing Sheets

See application file for complete search history.
